VARIABLE-SELECTIVITY RADIO RECEIVER

Alfred Crossley, Chicago, Ill., assignor to Johnson
Laboratories, Inc., Chicago, Ill., a corporation
of Illinois

Application May 11, 1934, Serial No. 725,059

9 Claims. (Cl. 250—20)

This invention relates broadly to improvements in high-frequency amplifying systems, and more particularly to systems designed to be operated at a fixed frequency, such for example as those in the intermediate-frequency amplifiers of superheterodyne receivers. In general, the selectivity of the receiver depends to a large extent upon the design of the intermediate-frequency amplifier, and it has been common practice to permanently establish the degree of selectivity at the time of the design and construction of the apparatus.

The object of this invention is to provide means whereby the degree of selectivity of the receiver may be varied at the will of the operator. Another object of the invention is to provide means whereby the overall fidelity or tonal reproducing properties of the receiver may be adjusted to suit the requirements of the person operating the receiver.

20 A further object of this invention is to provide means for obtaining any of the above-mentioned qualities by various coupling systems with which are associated suitable mechanical means for indicating the adjustment prevailing at any time. 25 Still another object is to provide means for automatically securing a desired adjustment of selectivity or fidelity for each of a plurality of channel positions of the station-selecting means of the receiver.

30 Additionally, it is an object of this invention to provide adjustable coupling means for varying the coupling from substantially zero to any predetermined value, the upper limit of coupling being independent of and not subject to control by the operator.

At the present time, radio broadcast stations transmit on assigned frequencies ten kilocycles apart. The resultant ten-kilocycle channel width permits the transmission of side-band frequencies up to 5000 cycles. The ideal receiver for operation under these conditions would have a rectangular "selectivity curve" (response vs. frequency) just ten kilocycles wide. It would be capable of receiving everything being transmitted in a given channel and of excluding all other signals.

In practice, however, it is not possible to obtain a straight-sided selectivity curve, and hence some sacrifice of the higher side-band frequencies must be made to insure satisfactory separation of broadcast stations transmitting on adjacent channels. The extent to which this compromise between selectivity and fidelity must be carried is largely determined by local conditions, includ-

ing the requirements of the person operating the receiver and the relative field strengths of the various broadcast stations. Hence it is practically impossible to so design a radio receiver that it will give entirely satisfactory reception in widely varying circumstances. For example, a receiver having sufficient selectivity to permit of satisfactory reception from a distant broadcast station operating on a channel adjacent to that of a strong local station would attenuate the higher side-band (audible) frequencies so seriously that it could not give substantially faithful reproduction from a near-by station operating in a channel somewhat removed from other powerful stations.

The means disclosed in this invention permit the degree of selectivity to be readily varied to meet the requirements of any location or the wishes of any operator, within wide limits. Furthermore, the limits may be accurately predetermined and the setting definitely indicated, or even automatically established for certain channels. It will be understood that this selectivity adjustment will also act as an adjustment of the overall fidelity of the receiver, since the amount of side-band attenuation and hence the relative strength of the higher audible frequencies will depend upon its setting. Thus the operator of the receiver rather than the original designer is the final judge regarding the most satisfactory compromise between selectivity and fidelity for any given conditions.

The objects of this invention are attained by varying the amount of coupling between successive stages in the intermediate-frequency amplifier of the receiver. This coupling may be entirely electromagnetic, entirely electrostatic, or electromagnetic and electrostatic combined. The coupling device usually consists of first and second windings, and in some cases includes auxiliary capacitance to provide electrostatic coupling. Even without this auxiliary capacitance, there is usually a small amount of electrostatic coupling due to the capacitance between the high-potential leads to the coils.

One embodiment of this invention utilizes a coupling device having a small fixed amount of electrostatic coupling, provision being made to vary the electromagnetic coupling by changing the relative positions of the first and second coils. In another embodiment, the coils are so positioned with respect to each other that there is substantially zero electromagnetic coupling. The electrostatic coupling in this case is varied by changing the capacitance of a condenser con-

nected between the high-potential terminals of the two windings. In a modified form of this embodiment, the capacitive coupling means may be associated with the low-potential terminals 5 of the two windings.

Preferred embodiments of this invention utilize coils with ferro-magnetic cores. These cores consist of finely-divided individually insulated iron particles compressed with a binding material to make a core body. Cores of this type, suitable for use at high frequencies, are disclosed in British Patents Nos. 366,475 and 403,368, and have recently been described in numerous publications in the United States and abroad.

10 The inductances are preferably designed in accordance with the United States Patent No. 1,978,568, issued October 30, 1934 and entitled High-frequency inductance. Each inductance consists essentially of a tubular cylindrical core 20 of the type described, with a pancake universal winding at its center, the length of the winding being usually from three-eighths to two-thirds of the radial depth, the length of the core being from 2½ to 5 times the length of the winding.

25 It is to be understood that air-core or other types of coils may be used in embodiments of the present invention, without exceeding the scope thereof. A lesser degree of efficiency will be obtained, however, in the general performance of 30 the system.

For a complete understanding of the invention, the following description should be read in connection with the accompanying drawings, in which—

35 Figure 1 is a cross-sectional side elevation of one desirable embodiment of the invention;

Figure 2 is a front elevation of a manual control device which may be used in conjunction with the invention;

40 Figure 3 is a cross-sectional side elevation of another embodiment of the invention;

Figure 4 is a wiring diagram showing how the embodiment of Figure 1, or a similar embodiment, is to be connected;

45 Figure 5 is a wiring diagram showing how the embodiment of Figure 3, or a similar embodiment, is to be connected;

Figure 6 is a schematic front elevation showing one form of the invention arranged for automatic operation in conjunction with the station 50 selecting means of the receiver; and

Figure 7 is a view of part of the contact member of the automatic device indicated in Figure 6, taken on the line 7—7 of Figure 6.

55 Referring to Figure 1, the embodiment shown varies the electromagnetic coupling between the coils in each of the two interstage coupling devices by moving one coil relatively to the other. A shaft 1 is supported by the H-shaped coupling 60 device frame 2. Movable coil 3 is supported between sections of the shaft 1 by means of insulating members 4, which are provided with studs fitting into the tubular core of coil 3, these studs being held in place by any suitable cement. The 65 members 4 are provided with shoulders 5 to provide a thrust bearing against frame 2. The coil 3 is so mounted that its axis intersects the axis of shaft 1 by an angle θ , which is of the correct value to give the desired degree of maximum coupling when the coil 3 is so positioned that its axis lies in a vertical plane also containing the axis 70 of the shaft 1.

The fixed coil 6 is mounted with its axis vertical, its tubular core being suitably cemented 75 over a stud extending vertically from the cross-

member of the frame 2. The shaft 1 passes through a hole 7 in the front panel 8 of the receiver, and may be rotated manually by means of knob 9. Its position is indicated by means of an escutcheon 10, suitably attached to the panel 8. 5 Each coupling device is provided with a shield 11, having a removable cover 12, and attached to sub-panel 13 by means of rivets 14 or by other suitable means. The control is arranged to operate the two devices simultaneously by means of 10 the coupling 15. Additional coupling devices may be added and will be operated by the coupling 15a.

This method has the advantage of providing 15 a very gradual adjustment of the coupling, and an adjustment which is not disturbed by vibration. It is to be understood that modified forms for obtaining a change in the degree of coupling 20 which may suggest themselves to those skilled in the art fall within the scope of this invention, the above-described embodiment representing a preferred form.

Figure 2 shows one form of escutcheon which 25 may be used to indicate the degree of selectivity for which the adjustment is set. In certain applications, the escutcheon may preferably bear the words "local" and "distance" instead of numbers, the local position corresponding to the minimum selectivity setting and the distance position to the maximum selectivity setting. Other 30 variations will readily occur to those skilled in the art, according to the particular application of the device.

In the embodiment shown in Figure 3, the 35 coils 3 and 6 are so placed with respect to each other that there is substantially zero electromagnetic coupling between them. Electrostatic coupling is used in this embodiment of the invention, and it is obtained by connecting an adjustable condenser between the high-potential 40 terminals of the first and second windings. Condenser plate 16 is secured to a square insulating rod 17 by any suitable means, such as a set screw inserted in a collar attached to plate 16. The fixed condenser plate 18 is secured to the 45 top 19 of the shielding can 11 by means of an insulating bracket 20. The rod 17 has attached to it a threaded metal rod 21 which engages the threaded inside portion 22 of the knob 23. Square holes in the shielding can 11 prevent the 50 rod 17 from rotating when the knob 23 is turned. Front panel 8 or a suitable bracket attached to the sub-panel 13 is located between the shoulder of threaded sleeve 22 and thrust disc 24, thus preventing axial movement of the rotating parts. 55 A set-screw collar 25 is provided to limit the motion of plate 16 toward plate 18, and hence the maximum amount of electrostatic coupling may be definitely set. Due to the screw movement, it will be necessary to provide a greater 60 arc of rotation for the knob 23 and consequently the escutcheon 10 may be of the full circular type instead of the arc or segment construction shown in Figure 2. The condenser plates 16 and 18 are connected by leads 26 to the high-potential 65 terminals of coils 6 and 3, respectively. The shield 11 associated with this unit is secured to the subpanel 13 by the conventional rivets 14.

Figure 4 shows the connections for a system 70 employing variable electromagnetic coupling. The antenna coil 27 is coupled to the radio-frequency coil 28, which is tuned to resonance by variable condenser 29 and connected in the control-grid circuit of the pentagrid converter 30. To simplify the diagram and explanation, I have 75

omitted the oscillating circuit which is associated with the pentagrid converter to obtain an intermediate frequency in the well-known superheterodyne manner. The plate circuit of the pentagrid converter includes the first winding 31 of an intermediate-frequency coupling device, the winding 31 being tuned by adjustable condenser 32 and variably coupled electromagnetically to the second winding 33, which is tuned by adjustable condenser 34. A second stage of intermediate-frequency amplification is shown with similar tuned circuits, and the second winding of the coupling device of this stage is in the input circuit of the second detector. This detector consists of the vacuum tube 35, its cathode circuit including a biasing resistance 36 shunted by a by-pass condenser 37. The output of the detector is supplied to the usual audio-frequency amplifier and output system. The plate circuits 20 of the pentagrid converter 30 and of the amplifier tube 38 have associated with them by-pass condensers 39 which substantially prevent the flow of intermediate-frequency current through the plate-voltage supply source.

Figure 5 shows an arrangement using the identical antenna input tuning system and pentagrid converter together with the first winding of the first intermediate-frequency coupling device, but the coupling is accomplished by means 30 of the condenser 40, which is mechanically adjustable as shown in Figure 3. The second stage of intermediate-frequency amplification and the second detector circuits have been omitted for the sake of simplicity. The condenser 40 is shown connected between the high-potential terminals of the first and second windings, but electrostatic coupling may also be obtained by the use of suitable condensers associated with the low-potential side of the coils. The coupling 40 condenser in that case will have much greater capacitance, and hence the preferred embodiment is that shown in the figure.

In Figure 6 is shown one arrangement for automatically changing the selectivity of the receiver when the station selector has certain predetermined settings. For example, it might be desirable to obtain the best possible fidelity from three or four nearby stations, and yet have the full selectivity of the receiver restored when it is tuned to all other frequencies. A rotary insulating disc 41 is mounted on the station selector or dial shaft 42, having at one end thereof the conventional dial 42a, and at its periphery carries several contacts 43 which, at 43a (Figure 7), extend over and are adjustable around the periphery of the disc. The contacts 43 are connected by means of suitable springs 43b to the shaft 42, which in turn is connected to a contact spring 42a. A contact spring 44 is arranged to make point contact, on occasion, with any one of the contacts 43, thus completing a circuit through the solenoid 45 and the source of potential 46. Each contact 43 is adjusted to correspond with the indicated dial position of each individual station on which best fidelity is desired. When current flows through the solenoid 45, its armature 47 is attracted. This motion is transmitted through link 48 to arm 49, and by means of link 50 and crank 51, the shaft 1 of the variable selectivity device is oscillated. When the contact is broken and current ceases to flow thru the solenoid 45, the shaft 1 is restored to the maximum selectivity position by means of spring 52. Hence it will be seen that the system is normally in the condition of maxi-

mum selectivity, but at predetermined settings of the station selector it is automatically adjusted to the condition of best fidelity or minimum selectivity. For automatic operation, the embodiment shown in Figure 1 has been found very 5 satisfactory, but it is within the scope of this invention to utilize other embodiments in conjunction with automatic operation. It is to be understood that other methods for obtaining automatic operation and methods for combined 10 manual and automatic operation will readily occur to those skilled in the art, and may be employed without exceeding the scope of this invention.

The details of the movable contact 43 are 15 shown in Figure 7. This figure is a sectional view of a portion of the insulating disc 41 with the contact 43 secured to it by the set screw 53. As shown in Figure 6, the insulating disc 41 has a 20 facial groove 41a which receives the inner end of the set screw. By loosening the screw 53, the contact 43 may be moved along the periphery of the disc 41 to the desired position. When the set screw 53 is tightened, the terminal 43a of the contact 43 presses against the disc 41 and holds the 25 contact 43 in that position.

In addition to the operating advantages which are obtained by the use of variable coupling between the first and second windings of the coupling devices, the adjustable feature permits 30 much more rapid and accurate initial alignment of the fixed-frequency amplifier at the time of manufacture. By setting the coupling at the minimum coupling position, each tuned circuit may be adjusted to resonance with practically no 35 interaction and with this initial adjustment any increase in coupling produces a broadening of the nose of the selectivity curve with no irregular sides or humps. This tuning operation is a simple one and only with this system can such a 40 simple method be employed to provide any desired degree of coupling. In the conventional type of coupling device the coupling is fixed which, where overcoupling is desired, makes tuning difficult due to reaction between the coils, 45 and resort has to be made to special oscillographic apparatus to tune such circuits.

The fact that I use variable electromagnetic coupling having fixed position of terminal or lead wires together with novel means for rotating the coil such that no variation in capacitance between coils is possible makes it practical to obtain this remarkable result. In the case where variable capacitive coupling is used, the desired result is obtained because it is possible to adjust 55 the electromagnetic coupling to zero. This zero coupling is obtained by positioning the horizontal core so that its axis is substantially at right angles to the axis of the lower core, as shown in Figure 3.

Having thus described my invention, what I claim is:

1. A fixed-frequency amplifier including pairs of coupled resonant circuits, each of said pairs comprising two ferro-magnetic-cored inductors, 65 one inductor in each of said pairs being rotatable and mounted at an oblique angle to its axis of rotation, and means for rotating said rotatable inductors in unison to vary the selectivity of said resonant circuits.

2. A fixed-frequency amplifier including pairs of coupled resonant circuits, each of said pairs comprising one fixed and one rotatable ferro-magnetic-cored inductor, said rotatable inductors being mounted with their axes at an oblique 75

- angle to the axis of rotation, and means for rotating said rotatable inductors in unison to vary the coupling between said coupled resonant circuits.
5. 3. A fixed-frequency amplifier including pairs of coupled resonant circuits, each of said pairs comprising one fixed and one rotatable ferro-magnetic-cored inductor, said rotatable inductors being mounted with their axes at an oblique angle to the axis of rotation, said oblique angle being chosen to determine the maximum degree of coupling in each of said pairs of coupled circuits, and means for rotating said rotatable inductors in unison to vary the coupling between 10 said coupled resonant circuits.
15. 4. A fixed-frequency amplifier including pairs of coupled resonant circuits, each of said pairs comprising one fixed and one rotatable ferro-magnetic-cored inductor, said rotatable inductors being mounted at a chosen oblique angle to their common axis of rotation, said common axis of rotation being at right angles to the axes of said fixed inductors whereby said rotatable inductors may be rotated to a position of substantially zero electromagnetic coupling to said fixed inductors, said oblique angle determining the maximum degree of coupling between said rotatable and said fixed inductors.
20. 5. A radio receiver having a fixed-frequency amplifier including coupling devices comprising first and second windings, each of said windings having a ferro-magnetic core, and two of said windings being eccentrically mounted for varying the selectivity of said receiver by rotating, in 25 unison, said eccentrically mounted windings and cores relatively to their respective cooperating windings.
30. 6. A radio receiver having a fixed-frequency amplifier including coupling devices comprising first and second windings, each of said windings having a ferro-magnetic core, and two of said windings being eccentrically mounted for simul- 35
- taneously varying the selectivity and the fidelity of said receiver by rotating, in unison, said eccentrically-mounted windings and cores relatively to their respective cooperating windings.
7. A radio receiver having a fixed-frequency 5 amplifier including coupling devices comprising first and second windings, each of said windings having a ferro-magnetic core, said receiver including means for varying the selectivity of said receiver by rotation in unison of at least two of 10 said windings and cores with respect to their respective cooperating windings and cores, whereby the degree of electromagnetic coupling therebetween is varied.
8. A radio receiver having a fixed-frequency 15 amplifier including coupling devices comprising first and second windings, each of said windings having a ferro-magnetic core, said receiver including means for simultaneously varying the selectivity and the fidelity of said receiver by 20 rotation of one winding and core in at least two of said coupling devices with respect to the other winding and core, whereby the degree of electromagnetic coupling therebetween is varied from a condition of loose coupling to a condition of 25 somewhat greater than optimum coupling.
9. A radio receiver having a fixed-frequency 30 amplifying circuit and a variable coupling in said circuit, combined with an electrical switching mechanism for effectuating desired selectivity characteristics of said circuit when receiving broadcast signals of different frequencies, said switching mechanism including an electrical circuit comprising a revolute insulating disc carrying an adjustable contact, a fixed contact 35 with which said adjustable contact may engage, a solenoid, a source of voltage for energizing said solenoid when said fixed and said adjustable contact are engaged, and a train of mechanisms actuated by the armature of said solenoid for 40 adjusting said variable coupling.

ALFRED CROSSLEY.
